UNITED STATES PATENT OFFICE

LOUIS D. GIBSON, OF NORWAY, MAINE, ASSIGNOR TO W. F. TUBBS COMPANY, OF NORWAY, MAINE, A CORPORATION OF MAINE

SKI BINDING

Application filed July 23, 1928. Serial No. 294,796.

My invention relates to ski bindings and relates particularly to ski bindings of the type provided with a rear strap and laterally adjustable toe irons, whereby the ski binding 5 may be employed in combination with a ski of given size to accommodate shoe soles of different thicknesses and width.

An object, therefore, of my invention is to provide a ski binding in which the toe irons 10 are variably adjustable to provide for the accommodation of different widths of shoe soles as may be desired which are adapted to be tightly secured to the ski by straps co-operating with the said binding.

Another object of my invention is to provide means cooperating with the toe irons of a ski binding and which will rigidly hold the two toe irons in any one of a number of different laterally adjustable positions to which 20 they may be adjusted.

Another object of my invention is to provide for a ski binding, the lateral adjustment of the toe irons in a simple expeditious manner.

Another object of my invention is to provide for the rigid mounting of laterally adjustable toe irons for a ski binding in a simple inexpensive manner.

Another object of my invention is to provide for the accommodation of shoe soles of different thicknesses within a ski binding in a very effective manner.

Another object of my invention is to provide for a greater variation in thickness of 35 shoe soles, than that usually provided in ski bindings now in use with which I am familiar.

Other objects of my invention and the invention itself will become more apparent 40 from the following description and in which description reference will be had to the accompanying drawings illustrating different embodiments of my invention.

Referring to the drawings:

Fig. 1 shows an inside elevational view of 45 an embodiment of my invention, together with fragments of the rear and toe harness straps, and of the ski to which the embodiment binding is illustrated as applied;

Fig. 2 is a plan view of the ski binding

together with a fragment of a horizontal medial section of the ski to which the binding is applied;

Fig. 3 is a side elevational view and Fig. 4 is a plan view of a toe plate of the binding 55 together with a supported toe clip;

Figs. 5 and 6 show, respectively, plan views of the bolt type toe clip, the view of Fig. 6 being taken at right angles to that of Fig. 5;

Fig. 7 shows an isometric view of a corrugated key employed in connection with the 60 said embodiment;

Fig. 8 shows the key of Fig. 7 in plan view;

Fig. 9 is a plan view of the clamping 65 wedges which may be employed, preferably in pairs, in combination with the said embodiment;

Fig. 10 is a longitudinal medial sectional view of a fragment of ski through a ski binding which is constructed in accordance with 70 the embodiment of my invention illustrated in the foregoing figures; and

Fig. 11 and Fig. 12, show, respectively, views taken in the same manner as that of Fig. 2, but each of different other embodiments of my invention;

Fig. 13 is a transverse sectional view of a ski taken through the slot and showing in elevation a corrugated key;

Fig. 14 is an isometric view of the corrugated key of Fig. 13; and

Fig. 15 is a plan view of the key of Figs. 13 and 14.

Referring first to the embodiment of my invention illustrated in Figs. 1 to 10, inclusive, the ski binding mechanism of my invention as embodied therein, comprises a pair of oppositely formed toe irons, the one comprising a base 3 and a side plate 5 and the other comprising a base 4 and a side plate 6. The bases 3 and 4 for the toe irons are projected from opposite sides of the ski 1, into the slot 2, the base 3 being superposed over the base 4, the thickness of the pair of bases being preferably great enough to fit 90 snugly between the upper and lower walls of the slot. The bases 3 and 4 are each provided with a serrated border 22 at their rear edge portions.

A metallic liner 23 having an outer face 100

- 24 of serrated form, and terminal prongs 25 are secured to the ski 1 within the slot by forcibly pressing the prongs 25 into the wood material of the ski at the rear of the slot. The rear surface of the liner 23 may be of any suitable form, such as the serrated form, as shown. The teeth formed by serrating the liner 23 are adapted to fit between the opposing teeth of the two base flanges 3 and 4, the liner being sufficiently wide from its top to its bottom edge to fit snugly between the upper and lower surfaces of the slot 2 and to make engagement with the serrated edges of the two flanges 3 and 4.
- 15 One or more pairs of wedges, such as 26—27, may be driven into the slot 2 intermediate its forward wall 28 and the forwardly disposed edges 29 of the iron flanges 3 and 4.
- 20 The toe iron base flanges 3 and 4 support at their oppositely disposed lateral ends, the toe iron side plates 5 and 6, respectively, to which by buttons 7 and 8, respectively, a rear strap 9 is adapted to be detachably connected by virtue of terminal hooks 10, one of which is secured by copper rivets 11 to each end of the strap, the slot 12 having the form illustrated with an enlarged portion 13 adapted to admit the head of the button 7 therethrough and a narrow end portion 14.
- 25 The head portion 15 of the vertical toe iron plates 5 and 6 is arcuately slotted at 16 to admit a looped end of a toe strap 17 which passes over the toe of the boot which is to be secured to the ski by the binding. The toe side plates 5 and 6 are also provided with preferably parallel slots 18 and 19 extending parallel to the longitudinal forward edge 20 of the side plates. The slots 18 and 19 have 30 successively diverging and converging walls in order, there being preferably a plurality of the diverging walls followed in each case by the same number of converging walls, for a purpose later to be more particularly described, but in general for the purpose of adjustably supporting a toe clip 21 extending inwardly from the plate 5 on the plate at a desired spaced relation to the top surface of the ski 1.
- 35 The toe clip is preferably formed as a head of a bolt 30 having a squared neck portion 31 and a threaded end 32 adapted to receive a nut 33. In a squared neck, the bolt is adapted to snugly fit within one of the squared openings 34, 35 and 36 of either of the slots, so called, 18 or 19. The interconnecting squared openings are formed, as shown, by the diverging and converging walls of the slot. A pair of the toe clips 21 is affixed to the side plates 5 and 6, respectively, by inserting their threaded ends 32 oppositely from the inner surface of the plates through a selected one of the interconnecting squared openings 35 or 36 of the slots 18 or 19 and the nuts 33 are threaded lightly on the bolts 30 to secure

the toe clips in adjusted position. When so placed the squared neck 31 engages with the surfaces of the squared slot to prevent rotation of the clip.

The link connector for detachably securing the ends of the rear strap 9 to the side plates comprises, as shown, a pair of buttons 7 and 8 riveted tightly onto the trailing portion of the side plates and having enlarged heads adapted to be projected into the enlarged opening 13 through the fastener 10 and then the fastener is moved rearwardly to effect a disposition of the reduced neck portion of the buttons within the reduced slot at 14, which interconnects with the large opening 13.

From the foregoing, the operation of the ski binding of the embodiment of my invention illustrated in Figs. 1 to 10, inclusive, will be readily understood. The user projects the toe of his boot between the toe plates 5 and 6 with the laterally projecting wall portion projected below the toe clips 21. The side plates 5 and 6 extend convergingly towards the front of the ski, so that the end of the boot, when the rear harness 9 is placed around the heel, will be wedged forwardly between the side plates and restrain from lateral upward movement for engagement between the upper surfaces of the sole and the toe clips. The base flanges 3 and 4 pressed rearwardly by a great pressure exerted between the wedges 26 and 27 to effect a very tight close-fitting engagement between the serrated edges of the flanges and the serrated surface of the liner 23, the teeth of the liner and plates being interlocked so that lateral movements of the flanges relative to the liner is effectually prevented, the liner by virtue of the pressure effected by the wedges interlocking the side plates and the locking of both to the ski.

In Fig. 11, another embodiment of my invention is provided with no metallic liner 23, but interlocking of the metallic base flanges 3' and 4' and locking of the base flanges to the ski 1' is effected by the teeth 44 of the serrated edges 22 being forced into the wood material of the ski slot vertical rear wall so as to form this wall to a complementary serrated form.

This may be accomplished by a special pressing operation prior to the driving of the wedges 26' and 27', or, especially where the wood material of the ski is not too hard, is relied upon to effect sufficient pressure on the plate flanges to form the rear wall of the slot, such a formed rear wall making engagement with the serrated edges will prevent lateral movement of the flanges within the slot.

In Fig. 12, an arrangement is illustrated varying from the above in that a plurality of pressure plates 39, 40, 41 and 42 are illustrated as being interposed between the front wall 28' of the slot 2 and the wedges 26'' and 27''. One of these, the pressure plate 42, being illustrated as making locking engagement by its

serrated surface 24' with forwardly disposed serrated edges 51 and 52 of the toe iron base flange 3" and 4". The plates 39, 40, 41 and 42 are all preferably generally of the 5 form of the liner 23, although the pressure plates may be made without terminal prongs, as illustrated.

In the embodiment of my invention illustrated in Figs. 1 to 10, inclusive, the liner 3 is 10 serrated to effect interlocking of the toe iron base flanges to prevent relative lateral movements thereof and moreover to effect locking of each of the base flanges to a lateral wall of the slot.

15 Figs. 14 and 15 illustrate, respectively in isometric and plan view, a form of plate interlocking key adapted to be substituted for the key of Figs. 7 and 8.

The element of Figs. 8 and 7 is of corrugated 20 form being angularly bent at short intervals throughout its length and terminates at one side in sharpened ends 62 and 63, Fig. 15, which are adapted to serve substantially the same purpose as the end prongs of Fig. 8, and 25 to all intents and purposes are end prongs for the key element, though of short length. The key of Figs. 14 and 15 is preferably bowed, the generally concavely curved surface having the terminal prongs 62 and 63 30 projecting from its face.

These prongs make an initial bite into the wood material of the ski in a manner analogous with the prongs as shown in Fig. 2, though they do not project so deeply.

35 In using the generally concave convex key of Figs. 14 and 15, it is placed with the teeth projecting from its generally convex side toward the teeth 22 and 24 of the plate bases 3 and 4 and interlocked with these teeth when 40 the wedges 26 and 27 are driven home, as in Fig. 2.

The inherent resiliency of the key 60 resisting the flattening effort imparted by the driven wedges maintains at all times resiliently 45 maintained contact between the several sets of teeth for the plate bases and key. The end prongs 61 and 62 and the intermediate serration points engaging the wood material at the end surface of the slot for 50 the ski 1, prevent lateral movement of the locked plate bases in the slot. Fig. 12 shows the key 60 in one embodiment of my invention.

In the embodiments of my invention illustrated in Figs. 11 and 12, reliance is mainly placed, in both said embodiments, upon the 55 forming of a wooden serrated lateral slot surface for effecting locking of the base flanges to the ski. Although in Fig. 12, interlocking of the two base flanges is made additional certain by the provision of the pressure plate 42 having the teeth of its rearwardly disposed surface projected in common between teeth of the two base flanges.

60 In Figs. 13 and 14, I have shown a method

of affixing the corrugated key in the slot which extends transversely through the ski, without resorting to the pointed ends of the embodiment of Fig. 7. The key 60 which is slightly curved in a vertical direction in the portion intermediate its ends, substantially as shown, is inserted into the slot with the corrugated sides horizontal and then rotated about its longitudinal axis, in the slot, through an arc of 90°. The ends of the key, which touch the line X—X, Fig. 14, dig into the material of the ski at the portions adjacent the edges of the ski and the intermediate upper portion 61 engages the upper wall of the slot.

Having thus described my invention in several embodiments, I am aware that numerous and extensive departures may be made from the embodiments herein illustrated and described but without departing from the spirit of my invention.

I claim:

1. In a ski binding, in combination with a transversely slotted ski, of a pair of toe irons, each having upstanding lateral toe engaging portions and base flanges, the flanges of the toe irons being projected from opposite sides of the ski into the slot and disposed in superposed relation therein, and a common key effecting interlocking of the base flanges engaging a lateral edge of each flange, each of the flanges having an edge portion indented with respect to a portion of the key, and means including end prongs for said key indented into the wood material of the slot walls to restrain the flanges and key from lateral movements in the slot.

2. In a ski binding, in combination with a transversely slotted ski, of a pair of toe irons, each having upstanding lateral toe engaging portions and base flanges, the flanges of the toe irons being projected from opposite sides of the ski into the slot and disposed in superposed relation therein, and a common key effecting interlocking of the base flanges engaging a lateral edge of each flange, and means including end prongs for said key indented into the wood material of the slot walls to restrain the flanges and key from lateral movements in the slot, said key comprising a toothed metallic plate, portions of the teeth of which being projected between complementary teeth formed in a corresponding edge of each of the flanges.

3. In a ski binding for transversely slotted skis, a liner element having teeth formed thereon on both of its opposite sides, a slot end wall having a toothed surface, of a pair of toe irons for each side of the ski to which the ski harness may be secured, each iron comprising an oppositely extending base flange projected from opposite sides of the ski in superposed relation into the slot and each of said base flanges being provided with a tooth adapted to be interchangeably received between pairs of teeth provided on the

serrated surface of said liner, and means effective to tightly press the toothed portions of the flanges and liner together, and teeth projecting from sides of said key into the toothed surface of said slot end wall.

5. In a ski-binding, in combination with a pair of toe irons having a pair of opposite laterally disposed upstanding flanges, and a base therefor, means to secure the irons to the ski by their base portions, and a pair of shoe sole retaining toe clips carried by the flanges, one by each flange, and comprising an elongated toe clip extending inwardly therefrom, a stem for the clip integrally secured thereto at one side of the longitudinal middle thereof, said stem comprising a neck of polygonal cross-sectional form, each of the flanges comprising openings therethrough of such polygonal form as will receive the neck projected therethrough, and adapted to make close-fitting engagement with the polygonal walls of the stem, and means disposed at the outer sides of the flanges adapted to prevent displacement of the clips, said neck adapted to be inserted through its flange opening in either of two oppositely rotated positions, whereby said clip may be adjusted to a greater or less distance from the base to accommodate shoe soles of different thicknesses.

30. In a ski binding, in combination with a transversely slotted ski, of a pair of toe irons, each having upstanding lateral toe engaging portions and base flanges, the flanges of the toe irons being projected from opposite sides of the ski into the slot and disposed in superposed relation therein, and a common key effecting interlocking of the base flanges engaging a lateral edge of each flange, and means to restrain the flanges and key from lateral movements in the slot, said key comprising a toothed curved metallic plate, portions of the teeth of which are projected between complementary teeth formed in a corresponding edge of each of the flanges.

45. In a ski binding, in combination with a transversely slotted ski, of a pair of toe irons, each having upstanding lateral toe engaging portions and base flanges, the flanges of the toe irons being projected from opposite sides of the ski into the slot and disposed in superposed relation therein, and a common key effecting interlocking of the base flanges engaging a lateral edge of each flange, and means to restrain the flanges and key from lateral movements in the slot, said key comprising a toothed metallic plate, bowed in a direction laterally of said teeth, portions of the teeth of which being projected between complementary teeth formed in a corresponding edge of each of the flanges.

In testimony whereof I hereunto affix my signature this 16th day of July, 1928.

LOUIS D. GIBSON.
